UNITED STATES PATENT OFFICE.

KENRIC JAMES McMULLEN AND MARK HEATON ROBINSON, OF RUGBY, ENGLAND, ASSIGNORS TO WILLANS AND ROBINSON, LIMITED, OF RUGBY, ENGLAND.

EXPLOSION-ENGINE.

SPECIFICATION forming part of Letters Patent No. 758,189, dated April 26, 1904.

Application filed August 27, 1903. Serial No. 170,982. (No model.)

To all whom it may concern:

Be it known that we, KENRIC JAMES McMULLEN and MARK HEATON ROBINSON, engineers, subjects of the King of Great Britain, residing at Victoria Works, Rugby, England, have invented certain new and useful Improvements in Explosion-Engines, of which the following is a specification.

This invention is applicable to gas or oil engines working on the well-known four-stroke or Otto cycle, in which, owing to high speed of rotation, it is desired to cushion the line of working parts in such manner as to retain the brasses in "constant thrust." Such engines are preferably of the inverted vertical pattern, and the following description applies thereto; but they may also be made horizontal or inclined. The working cylinder is single-acting and may be open at the lower end. The piston is connected by a piston-rod to a guide-piston working in a guide-cylinder, the piston-rod passing through a gland in the cover of such guide-cylinder. The guide working in the said cylinder is preferably in the form of a trunk-piston, to which a connecting-rod is attached in the usual manner. The guide-cylinder forms also the air-cushion cylinder, operating substantially in the same manner as in the well-known Willans steam-engine. At the lower end of its stroke the guide-piston uncovers a port which is in communication with the atmosphere, or air may be admitted by an automatic non-return valve. The air shut in is as the piston rises compressed in the upper end of the guide-cylinder and gives the desired cushioning effect. On the next down-stroke it expands and does work upon the guide-piston with very little loss. Such cushioning effect, however, is not required upon those up-strokes during which the air or gas and air required for the next explosion are being compressed in the working cylinder. Such compression in the working cylinder gives of itself the necessary cushioning, and if air-cushioning in the guide-cylinder is added at the same time the total holding-down effect upon the crank-pin will be much in excess of what is required and will subject the mechan-

ism to needless stresses and to increased friction.

In order to make beneficial use of the compression of air in the guide or air-cushion cylinder during those strokes when it is not required for cushioning effect, we arrange that the top of the said cylinder shall communicate by a port in which there is a valve with a reservoir. At the lower end of the working cylinder is a port which is uncovered by the piston at the end of its downstroke. Such port is in communication with the reservoir by a passage in which there is also a valve, or the piston itself, if made sufficiently long to keep the ports closed at all times except when it is at the bottom of its stroke, may itself act as the valve. During the upstroke, in which cushioning in the guide-cylinder is required, the valve in the port leading from the guide-cylinder to the reservoir is closed and air is compressed in the guide-cylinder, not being able to escape into the reservoir; but during the intermediate strokes, when cushioning in the guide-cylinder is not required, the valve is opened and the air is allowed to pass into the reservoir, the proportions of the latter being such that the highest pressure reached is moderate, amounting to only a few pounds per square inch. The reservoir will thus be replenished during every compression-up-stroke of the working piston, and the air will be retained in the reservoir until the end of the succeeding working downstroke, when, the valve between the reservoir and the port in the working cylinder being opened, the air will rush into the working cylinder as soon as the piston uncovers the port and for as long as it remains uncovered. This air will act as a scavenging charge, blowing the products of combustion out through the exhaust-valve and more or less insuring that the clearance-space shall be filled with pure air at the end of the succeeding up or exhauststroke. During the next downstroke, when air or air and gas are being drawn into the working cylinder for subsequent compression, the valve between the reservoir and the port in the working cylinder may be kept closed, so that when

the port is uncovered by the piston no air shall enter the cylinder. During this down-stroke air enters the guide or air-cushion cylinder by an automatic valve, which is kept closed by the pressure of the air in that cylinder at all other times, except when the pistons are at or near their lowest position, when there is naturally no pressure in the air-cushion cylinder. Alternatively the disposition of valves may be such that a portion only of the contents of the reservoir shall be driven into the working cylinder as a scavenging charge and some shall be retained in the reservoir to be sent into the cylinder at the completion of the charging downstroke, with the effect of adding to the weight of the explosive mixture in the cylinder at that time.

In the accompanying drawings, Figure 1 shows a vertical section of a single-cylinder engine constructed according to this invention. Fig. 2 shows a vertical section of a portion of such engine embodying a modification.

A is the working cylinder, in which the single-acting piston B reciprocates. The working piston B is connected by the piston-rod C C to a guide-piston D, working in a guide-cylinder E, the connecting-rod F being attached to the guide-piston in the usual manner. At the lower end of its stroke the guide-piston D uncovers a port or ports G G, which are in communication with the atmosphere, or the ports G may be replaced by an automatic non-return valve P, as shown in Fig. 2. The air shut in as the piston D rises is compressed in the upper end of the guide-cylinder E and gives the desired cushioning effect. On the next downstroke or suction-stroke it expands and does work upon the guide-piston D, and thus prevents any reversal of the direction of strain on the connecting-rod, which is always kept in compression.

In order to make beneficial use of the compression of air in the guide or air-cushion cylinder E during the compression-stroke when it is not required for cushioning effect, we arrange that the top of the said cylinder E shall communicate by a port H, in which there is a valve J, with a reservoir K K K.

At the lower end of the working cylinder A is a port or ring of ports L L L, which are uncovered by the piston B at the end of its downward stroke. Such ports are in communication with the reservoir K.

During the upstroke, in which cushioning in the guide-cylinder E is required, the valve J is closed and air is compressed in the guide-cylinder E; but during the intermediate strokes, when cushioning in the guide-cylinder E is not required, the valve J is opened and the air is allowed to pass into the reservoir K K K, the proportions of the latter being such that the highest pressure reached is moderate, amounting only to a few pounds per square inch. The reservoir K K K will thus be replenished during every compres-

sion-upstroke of the working piston B and the air will be retained in the reservoir K K K until the end of the succeeding working downstroke, when the port or ports L L L between the reservoir K K K and the working cylinder A being opened the air will rush into the working cylinder A as soon as the piston B uncovers the port or ports and for so long as the port or ports remain uncovered. The air will act as a scavenge charge, blowing the products of combustion out through the exhaust-valve M and more or less insuring that the clearance-space shall be filled with pure air at the end of the succeeding up or exhaust stroke. During the next downstroke, when the air and gas are being drawn into the working cylinder A through the admission-valve N for subsequent compression, communication is established between the reservoir and the cylinder at the bottom of the intake-stroke. If there is any pressure left in the reservoir, all that happens is that there is a slight addition to the air in working cylinder A. During the downward stroke air enters the guide or air-cushion cylinder E by the ports G or automatic valve P.

R indicates a shaft carrying cams $r r' r''$ for operating the valves N, M, and J, respectively.

What we claim is—

1. In a four-stroke cycle explosion-engine the combination with the working cylinder and piston of an air-cylinder and piston connections between the two pistons such that they move together, an air-reservoir, means for admitting air to the air-cylinder before each instroke of the working piston, a valve admitting air to the reservoir from the air-cylinder during the compression-stroke of the working piston and preventing the escape of air from the air-cylinder during the exhaust-stroke, and means for admitting air from the reservoir into the working cylinder during the exhaust-stroke of the working piston.

2. In a four-stroke cycle explosion-engine the combination with the working cylinder and piston of an air-cylinder in line with the ordinary cylinder a piston in the air-cylinder a piston-rod connecting the two pistons, an air-reservoir, means for admitting air to the air-cylinder before each instroke of the working piston, a valve admitting air to the reservoir from the air-cylinder during the compression-stroke of the working piston and preventing the escape of air from the air-cylinder during the exhaust-stroke of the working piston and means for admitting air from the reservoir into the working cylinder during the exhaust-stroke of the working piston.

3. In a four-stroke cycle explosion-engine the combination with the working cylinder and piston of an air-cylinder and piston connections between the two pistons such that they move together, an air-reservoir, means for ad-

mitting air to the air-cylinder before each in-stroke of the working piston, a valve admitting air to the reservoir from the air-cylinder during the compression-stroke of the working piston and preventing the escape of air from the air-cylinder during the exhaust-stroke of the working piston and a port in the outer end of the working cylinder in communication with the reservoir.

10 4. In a four-stroke cycle explosion-engine the combination with the working cylinder and piston, of an air-cylinder in line with the ordinary cylinder, a piston in the air-cylinder, a piston-rod connecting the two pistons, an
15 air-reservoir, means for admitting air to the

air-cylinder before each instroke of the working piston, a valve admitting air to the reservoir from the air-cylinder during the compression-stroke of the working piston and preventing the escape of air from the air-cylinder during the exhaust-stroke of the working piston and a port in the outer end of the working cylinder in communication with the reservoir. 20
